STAMP HOLDER

Alfred Gunning, Houston, Tex.

Application February 25, 1942, Serial No. 432,349

1 Claim. (Cl. 229—87.5)

The present invention relates to new and useful improvements in holders for postage stamps and similar stamps or articles in strip form, and the invention has for its primary object to provide a holder including a plurality of foldable sections upon which the stamps may be positioned for folding into a compact form whereby to protect the adhesive surface of the stamps from moisture while the same are carried in the pocket, billfold, or other container.

A further object of the invention is to provide a folder of this character of simple and practical construction, which is neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:

Figure 1 is a plan view showing the holder in closed position.

Figure 2 is a plan view of the flank of paper from which the holder is constructed.

Figure 3 is a fragmentary plan view of the blank showing the flap for the inner end of the strip of stamps in closed position.

Figure 4 is a fragmentary sectional view taken substantially on a line 4—4 of Figure 3.

Figure 5 is a plan view of a blank strip of material embodying a modified form of holder.

Figure 6 is a similar view showing the first step in forming the stamp-receiving pocket.

Figure 7 is a similar view showing the completed holder in open position.

Figure 8 is a fragmentary plan view of the rear pocket.

Figure 9 is a sectional view taken on a line 9—9 of Figure 7, and

Figure 10 is an edge elevational view.

Referring now to the drawings in detail and with particular reference to Figures 1 to 4, inclusive, the numeral 5 designates a strip of paper having transversely extending fold lines 6 arranged in spaced parallelism, the longitudinal side edges of the strip, at one end, being formed with flaps 7 and 8 at opposite edges of the strip, the flaps being of a width substantially equal to the width of the end panel 9 and of a length slightly less than the width of the strip 5 to permit folding of the flaps in overlapping relation.

The flap 7 is formed with a longitudinally extending slit 10 and the outer end of the flap 8

is formed with a tongue 11 adapted to be inserted in the slit 10 when the flaps are in folded position. The flaps 7 and 8 are connected to the side edges of the panel 9 by fold lines 12.

5 Adjacent the panel 9 is a panel 13 projecting from the opposite side edges of which are tabs 14 and 15, the tabs 14 and 15 being free of the flaps 7 and 8 and the flaps 14 and 15 are of an area less than the area of the flaps 7 and 8 as shown to advantage in Figure 2 of the drawings. The tabs 14 and 15 are adapted to be folded inwardly in overlapping relation upon the panel 13 and free therefrom, the overlapping edges of the tabs 14 and 15 being secured by mucilage or the like.

10 The edges of the tabs 14 and 15 remote from the flaps 7 and 8 are formed with notches 16 to facilitate the placing of one end of a strip of postage stamps or the like 17 under said flaps. 15 The perforated edges 18 of the stamps are positioned in registry with the folds 6 of the strip of material 5, so that the stamps will be folded along their perforated edges, together with the strip.

20 The strip 5, outwardly of the panel 9, is folded from the fold lines 6, together with the postage stamps, and the panel 13 is likewise folded, together with the remaining portion of the strip upon the panel 9 and secured in folded position by the flaps 7 and 8.

25 In the modified form of the invention illustrated in Figures 5 to 10, inclusive, the strip of paper is shown at 19 having the transverse fold lines 20 defining panels 21.

30 The end panel 22 is provided with a curved edge 23 and adapted for folding upon the adjacent panel 24, as shown in Figure 6, the curved edge facilitating the insertion and removal of the end stamp of a strip of stamps. The side edges of the panel 22 are provided with foldable tabs 25 and 26 adapted for folding in overlapping relation behind the panel 24 and cemented to each other. One edge of the tabs 25 and 26 are reduced in width, as shown at 27, to facilitate insertion and removal of the tongue 28 at the other end of the strip, when the panels are folded one upon the other.

35 The stamps are of an area substantially equal to the area of the panels and are folded with the panels into a compact form. The gummed surface of the stamps are thus separated from each other and protected from moisture while being carried in a person's pocket or purse.

40 It is believed the details of construction and manner of use of the device will be readily un-

derstood from the foregoing without further detailed explanation.

Having thus described the invention what is claimed as new is:

A postage stamp holder comprising a strip of flexible material having spaced parallel transverse fold lines defining individual backing sections for stamps in strip form when placed upon the strip of material, said strip of material being folded along said transverse fold lines, tabs at

10

the side edges of the strip adjacent one end of the strip and foldable upon the strip to form a pocket for receiving one end of a strip of stamps, and a second pair of tabs carried by the side edges of the strip of material at its end adjacent the first named tabs and foldable in interlocking engagement over the folded strip and pocket to retain the same in folded position.

ALFRED GUNNING.
